UNITED STATES PATENT OFFICE.

JOSEPH ALEXANDER MANNING, OF PAWTUCKET, RHODE ISLAND.

MECHANICAL EYE.

1,137,772.

Specification of Letters Patent. Patented May 4, 1915.

Application filed June 12, 1914. Serial No. 414,713.

To all whom it may concern:

Be it known that I, JOSEPH A. MANNING, a citizen of the United States, residing at Pawtucket, in the county of Providence and State of Rhode Island, have invented a new and useful Mechanical Eye, of which the following is a specification.

The present invention relates to improvements in mechanical eyes, and more especially to eyes for use in connection with dolls or other toy animals or manikins, one object of the present invention, being the provision of an eye supporting member having a plurality of co-acting attaching means for engagement with the head to which it is connected so that the support carrying the eye will be rigidly secured in place and be more durable than the forms of mechanical eyes now used.

20 A further object of the present invention is the provision of a metal eye, the parts of which are preferably stamped and attached together by co-operating means, thus producing an exceedingly durable as well as an inexpensive mechanical eye, and one which may be attached in place without the necessity of producing an opening in the top of the head of the object as is the usual practice.

30 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

40 In the drawings—Figure 1 is a sectional view taken through a doll head adjacent one eye aperture thereof with the preferred form of mechanical eye in vertical section. Fig. 2 is a rear plan view of the mechanical eye as shown in Fig. 1. Fig. 3 is a section taken on line 3—3 of Fig. 2 showing the adjacent portion of the doll head. Fig. 4 is a perspective view of the rear plate of the mechanical eye. Fig. 5 is a front elevation of the shield support for the mechanical eye. Fig. 6 is a vertical central sectional view through a modified form of mechanical eye. Figs. 7, 8 and 9 are detail views of parts thereof. Fig. 10 is a rear elevation of still another modified form of eye showing two of the members connected for movement in

unison. Fig. 11 is a view similar to Fig. 10 of still another modified form, the eyes being mounted for independent swinging movement. Fig. 12 is a view similar to Fig. 10 of still another modified form, the eyes being connected for both sleeping and wide awake as well as for side glancing movements and for movement in unison. Fig. 13 is a front perspective view of the supporting member for the eyes illustrated in Fig. 12. Fig. 14 is a longitudinal section through the bar for connecting the eyes in Fig. 12 for simultaneous movement. Fig. 15 is a vertical section through a metallic doll head showing the method of attaching the support thereto. Fig. 16 is a rear elevation of another modified form of mechanical eyes carried by the supporting member, as illustrated in Fig. 13. Fig. 17 is a top plan view thereof, the eyeball portion of the eye being shown in dotted lines. Figs. 18, 19, 20 and 21 are perspective views of details thereof. Fig. 22 is a view similar to Fig. 16 of still another modified form of mechanical eye. Fig. 23 is a top plan view thereof, a portion of the supporting member only being illustrated.

Referring to the drawings, H designates the doll head which may be taken indicative of any head to which mechanical eyes are to be attached, a concaved metal support 1, which is preferably made of stamped metal being provided with the eye aperture 2 for alinement with the eye aperture of the doll head, there being formed from the metal adjacent the opening 2, the forward tangs 3 and the rear tangs 4, as clearly shown in Fig. 5, there being two of each of these. In assembling the present support 1, the tangs 3 are pressed to engage the solid portion of the head adjacent the eye opening and the cementitious material. 7 and 8 is then rounded out and about the tangs adjacent the doll head so as to incase the tangs and the adjacent portion of the support around the eye opening 2 thereof so as to produce a reinforcement about the support and the adjacent portion of the eye aperture of the doll head H, to thus rigidly secure the support in place so that the same will not be accidentally removed due to the dropping or sudden jarring of the doll head. Two apertured lugs 6 are carried by the support 1, the purpose of which will presently appear.

The mechanical eye as illustrated in Figs. 1 to 4, consists of the semi-spherical mem-

ber 9 carrying the tangs or prongs 10 formed at the edge thereof and with the projecting lip 11. A plate 12 constitutes the back of the eye and is held in engagement with the member 9 by means of the bent tangs 10, the plate being provided with the two inwardly projecting lips or flanges 13 and 14, in the apertures of which are mounted the pintles 15 and 16 connected to the lugs of the plate 17, said plate 17 being provided with the oppositely extending arms 18 carrying the pins 19 which are adapted to fit within the apertured lug 6 of the support 1 and thus support the eye member for vertical swinging movement. The pintles 15 and 16 provide a means whereby the eye member is mounted for horizontal or glancing movement. A swiveling pin 20 is connected centrally of the plate 17 and swingingly attached to the lever 21 thereto, said lever being apertured at 22 for the sliding reception of the lug 23 of the plate 12. It will thus be seen that as the lever 21 is swung horizontally, that the engagement thereof with the lug 23 will impart a horizontal swinging movement to the mechanical eye upon the axis formed by the pins 15 and 16 to thus impart a glancing movement to the eye. A lug 25 is formed upon the backing 12 so as to limit the downward movement of the mechanical eye when the eye is in full open position.

In order to assist in causing the eye member to move by gravity, either to produce the open or closed condition or the glancing condition, a weight 26 is carried by the lever 21, the same being set therein, while in order to produce a unitary action between the two eyes, a pivoting pin or rivet 27 fitted in the lower end of the lever 21 is attached to the rod 28, which is similarly connected to the other eye.

In the form of eye shown in Figs. 6 through 9, the eye is made of semi-spherical sections 29 and 31, the member 29 being provided with the prongs or tangs 30, which are adapted to be bent upon and engage the member 31 to maintain the parts in the position shown in Fig. 6. The member 31 is provided with the lug 32, which limits the movement of the eye when the head is tilted to the rear to produce the sleeping effect, while the pintles 32' formed integral therewith are adapted to fit within the apertured lugs 6 of the shield supporting member 1. This eye is constructed for only the sleeping and wide awake effect. A weight 33 is attached to and carried by the rear section 31 at a point to assist in holding the eye in the desired position. A plate 34 is formed integral with the member 31 of the eye and depends downwardly having attached thereto in one instance, the pivot 37' for pivotally connecting the double lugged plate 35 in place for the sliding reception of

the free end of the rod 28', the other end of which is connected to the plate 34 of the other eye similarly to the connection thereof to the lever 21, as heretofore described.

In the form of mechanical eye as shown in Fig. 10, the member 29' is a hollow semi-spherical member made of stamped metal, the same having the integral lugs or pintles 32' for fitting in the apertured lug 6 of the shield 1, an arm or lug 37 being provided at the upper edge and carrying the weight 37' which assists the arm 38 and the weight 39 for imparting the desired vertical swinging movement to the eye. A rod 28' is pivotally connected by the rivet 27' to one of the arms 38 while a double lugged swiveled member 35' which is similar to the member 35 is connected to the arm 38 of the other eye for properly connecting the rod 28' so that the eyes will move in unison. By providing this particular swivel connection for the rod 28', it is not essential that the two supports 1 must be in exactly the same alignment, due to the peculiar shape of the head of the toy to which the eye is attached, as the swivel connection 27' and the double lugged member 35' take care of any inequalities.

In the form of mechanical eye shown in Fig. 11, the support 1 is constructed similar to the other supports of the apertured lugs 6 while the eye member has the forward portion 29' constructed similar to the member 29, of Fig. 6, a round back 31' similar to the back 31 being provided and having an inverted weight 33' and a pendant 34', the rod 28' being dispensed with so that the eyes have independent swinging movements. These eyes are constructed merely for the wide awake and sleeping effect and similar to that shown in Fig. 6.

In the form of eye shown in Figs. 12, 13 and 14, a single supporting member 40 for both mechanical eyes is provided, the same being provided with the apertured lugs 41, the purpose of which will presently appear, and with a plurality of tangs or prongs 43 adjacent the eye apertures 42, and the central prongs 44. Thus when this support is positioned in place, the tangs 43 engage the head adjacent the eye apertures thereof, while the tangs 44 engage the head at the rear of the nose bridge, cement being applied to properly hold the support 40 in place. By this means, the eye members, which are similar to the structure shown in Fig. 1, are assembled upon the support and in proper adjusted position after the support 40 is attached to the head. In this instance, a plate 17' having the pintles 19', engages the apertured lugs 41 and extends at the rear of both of the eye members 9', the swiveling rivets 20' being provided to properly attach and mount the lever 21' which is similar to the lever 21 heretofore

described, while the swiveling rivet 27^a is attached to the lower end of the respective levers and forms a pivoting connection between the bar 45 and the respective eye members, so that both eye members will move in unison to produce the wide awake and sleeping effect and the side glancing effect. The other details of this eye are as particularly set forth relative to Fig. 1 through Fig. 4, and need not be described in detail.

In the form of eye shown in Fig. 15, the doll head H' is formed of sheet metal, the shield 1^a in this instance being provided with the aperture 2^a, there being no tangs such as 3 and 4 provided but the metal of the doll head as at 46 is spun backwardly and around the rim of the aperture 2^a of the support 1^a, to thus fixedly attach the support to the metal doll head. By this means a neat finish looking from the face side of the head is provided and one in which the support 1^a is rigidly secured in place for the proper support of any of the respective eyes either for the wide awake or sleeping effect or for the side glancing effect.

As illustrated in Figs. 16 through 21, the supporting member 40', which is similar to the supporting member 40 of Fig. 12, is provided with the apertured lugs 41' while the eye carrying bar or member 47 is provided with the oppositely disposed pintles 50 for mounting within the lugs 41' so that the member 47 may be permitted a vertical swinging movement. This member, as clearly illustrated in Fig. 19, is provided with the bent portions 48 and 49 to accommodate as will later appear the sidewise or glancing movement of the eye members 67. Formed integral with the member 47 and depending therefrom is a plate 51 whose lower end is provided with the two offset portions 52 which provide the slot 53, the portion 51 thereabove being provided with segmental slot or aperture 54 while the upper portion is provided with the key-hole slot 55, the purpose of which will presently appear. Two pairs of arms 56 are also carried by the member 47 one to each eye member 67, and each arm is provided with a pin 57; the pins of each pair being extended in opposite directions to fit within the apertured lug 68 of the eye carrying member 67, so that the eye carrying member may have the glancing effect imparted thereto.

The plate or lever 58 is provided with the T-shaped head 59 bent at right angles to the body of the lever for insertion within the key-hole slot 55 of the member 47, at which point the same is pivoted for horizontal swinging movement, and provided with a pin 60 which extends through the arcuate slot 54 while in the lower end is provided the weight 61, the said lever 58 being extended through the slot 53 which limits the side-

wise movement thereof. The pin 60 enters the aperture 62 of the eye actuating bar 64, this bar 64 being provided with the hooked ends 65 which fit within the apertured lugs 66 of the eye carrying member 67, so that when the lever 58 is tilted in either direction, the eye member 65 will be operated so as to swing on its axis formed by the apertured lugs 68 and pins 57 to impart a glancing effect to the semi-spherical eye-ball carrying portion 69. It will thus be seen that when the lever 58 is tilted at either side, that both eye members will have the glancing effect imparted thereto, while when the head of the doll is reclined to a sleeping position, the member 47 carrying the eyes and the other parts will tilt to produce the sleeping effect in the mechanical eyes.

In the form of mechanical eyes shown in Figs. 22 and 23, the support 40^a which is similar to the support 40, is provided with the apertured lugs 41^a which receives the pintles 72 of the eye carrying bar 70, the said member 70 being provided with two concaved portions 71 which constitute the rear portions of the eyes, the forward portions 75 of which are secured thereto as in the other forms, there being formed integral with the member 70 intermediate of its length an actuating depending portion 73 carrying the weight 74. In this structure, the eye members are only permitted the sleeping effect.

What is claimed is:

1. The combination with an imitation head having an eye aperture, of a mechanical eye, including a support carrying an eye member, clamping two diametrically disposed means carried by the support for gripping the rim of the eye aperture of the head to hold the support relatively to the eye aperture, and a cementitious material covering the clamping means and adhering to the head and support to augment the attachment of the support to the head.
2. A mechanical eye, including a support having two eye apertures therethrough, two apertured lugs carried by the support one at each end thereof, means carried by the support adjacent the eye apertures for engaging an imitation head, means carried by the support intermediate of the eye apertures for engaging the imitation head, and two eye members swingingly mounted in the apertured lugs for movement in unison.
3. A mechanical eye, including a support having two eye apertures therethrough, two apertured lugs carried by the support one at each end thereof, means carried by the support adjacent the eye apertures for engaging an imitation head, means carried by the support intermediate of the eye apertures for engaging the imitation head, a plate pivotally mounted in the apertured lugs for vertical swinging movement, two

125
130

eye members attached thereto for movement therewith and for independent horizontal swinging movement, two levers swingingly connected to the plate adjacent the respective eye members, means for connecting the levers for movement in unison, and co-operable means carried by each lever and its respective eye member whereby horizontal swinging movement imparted to the lever will impart a glancing movement to both eyes of the eye members.

4. The combination with an imitation head, having an eye aperture, and a mechanical eye including a support carrying an eye member, two pairs of prongs dia-

metrically disposed and carried by the support, said prongs being shaped to fit upon and clamp the edge of the head adjacent the opposite sides of the eye aperture to maintain the support to the head, and a cementitious material covering the prongs and reinforcing the portion of the head adjacent thereto.

In testimony that I claim the foregoing as my own, I have hereto affixed my signature in the presence of two witnesses.

JOSEPH ALEXANDER MANNING.

Witnesses:

GEORGE S. LINCOLN,
HENRY W. POTTER.
